LEAKAGE MINIMIZING SHIELD FOR
ELECTRON DISCHARGE DEVICES

George F. Devine, Easton, Conn., assignor to General Electric Company, a corporation of New York

Application June 18, 1945, Serial No. 600,009

5 Claims. (Cl. 250—141)

1

This invention relates to electron discharge devices such as cathode ray tubes and particularly to apparatus for minimizing the leakage of current from such devices to the supporting structures thereof.

Cathode ray tubes commonly comprise an envelope within which is arranged an electron gun for producing a beam of electrons, together with an accelerating electrode and a fluorescent screen on which the beam is caused to impinge and produce a luminous spot the intensity of which may be varied in accordance with a signal introduced on a control grid in the path of the beam. Deflecting electrodes are also provided to determine the point on the screen where the beam falls. During the operation of cathode ray tubes the luminescent screen attains a high positive potential with respect to the cathode due to secondary emission. The supporting structure for a cathode ray tube frequently comprises a frame or collar arranged about the envelope of the tube peripherally of the luminescent screen, and there is a tendency for current to leak through the envelope to the supporting structure. The leakage is negligible in dry weather but during conditions of high humidity in the atmosphere the rate of leakage may become appreciable and as a result the signal portrayed on the luminescent screen is affected thereby. For example, the length of a horizontal trace on a cathode ray screen will change with the intensity of the signal so that if a cathode ray tube is provided to give a calibrated reading this reading will be in error when the atmospheric conditions change. Accordingly it is an object of this invention to provide an electron discharge device including an improved arrangement for minimizing the leakage of current from a high potential area of the interior surface of the envelope to the exterior.

It is another object of this invention to provide an electron discharge device such as a cathode ray tube including an improved arrangement for minimizing leakage from the fluorescent screen through the envelope and which is of simple construction and readily applied to cathode ray tubes.

The novel features which are believed to be characteristic of the invention are set forth with particularity in the appended claims. The invention itself, however, both as to its organization and method of operation, together with further objects and advantages thereof, may best be understood by reference to the following description taken in connection with the accompanying

2

drawing in which Fig. 1 is a side elevation, partly in section, of a portion of a cathode ray tube embodying the invention; Fig. 2 is a perspective view, partly broken away, of the external high voltage element shown in Fig. 1; Fig. 3 is a diagrammatic view of the cathode ray tube of Fig. 1 and its associated circuits; Fig. 4 illustrates a modification of the invention; and Fig. 5 is a sectional view of a portion of a tube similar to that of Fig. 1 showing a further modification.

The cathode ray tube illustrated in Fig. 1 comprises a glass envelope 1 including a neck portion 2, only a part of which is shown, and a bowl 3. The beam forming electrodes or electron gun (not shown) is arranged in the usual manner in the neck portion 2, and the face of the tube is provided with a fluorescent screen 4 which becomes luminescent when the electron beam impinges thereon. An accelerating electrode or anode 5 is provided on the inner walls of the bowl; this electrode may be a coating on the walls or a separate sheet metal electrode. A conducting terminal for the electrode 5 is secured on the outside of the tube as indicated at 6. In order to support the tube in the structure in which it is to be employed, a resilient collar 7 of rubber or other suitable material is placed about the tube at its greatest diameter around the periphery of the screen, and a viewing plate 8 is secured over the face of the tube in a suitable metal frame 9 which is fitted to the collar 7. An additional harness or girdle (not shown) is also employed to hold the collar on the bowl in the usual manner. The plate 8 may be provided with suitable scales or markings calibrated in accordance with the signals to be observed so that a direct reading may be obtained.

The tube is connected in a suitable circuit as indicated in Fig. 3. A suitable high voltage source 10 shunted by a resistor or potentiometer 11 is connected to the electrodes as illustrated. The cathode and first anode shown at 12 and 13, respectively, are connected to points of the potentiometer providing the required bias voltages; and a control grid shown at 14 is connected to a source of signals 15 to vary the intensity of the electron beam in accordance with the signal. The anode 5 is connected through the cap 6 to the high potential positive end of the potentiometer. During the operation of the cathode ray tube a high positive potential with respect to the cathode exists on the fluorescent screen 4 due to secondary emission. This potential may be of the same order of magnitude as the potential of the accelerating anode 5. There is a tendency

for current to leak off through the envelope to the supports and surrounding structure, and this tendency is particularly noticeable when there is moisture in the ambient air. The presence of leakage may be detected by changing the intensity of the electron beam; when leakage is present the length of the trace produced by the sweep of the beam changes when the intensity is changed. It is to be understood, of course, that suitable deflecting members (not shown) are provided about the neck 2 of the tube to deflect the beam in the desired directions and at the desired rates. In apparatus in which the trace of the beam of the screen is employed to determine quantities to be measured and in which it is important that the scale of presentation remain fixed, the presence of leakage greatly reduces the usefulness of the apparatus when moisture is present. In order to minimize leakage and thereby minimize the errors in interpreting the signal, a conducting band is provided about the outer wall of the envelope adjacent the periphery of the luminescent screen. As shown in Figs. 1 and 2, this band may comprise a loop of wire 16 connected by an insulated wire 17 to a loop 18 clamped about the terminal 6 of the anode 5, the loop 18 being made of phosphor-bronze or some other suitable material which can be clamped about the terminal. The wire 16 extends about the periphery of the envelope and may be held in place by the collar 7. When the cathode ray tube is in operation, the potential on the wire 16 is the positive potential of the accelerating anode 5. This potential is of the same order of magnitude as the positive potential on the fluorescent screen 4. The presence of the same positive potential on the outside of the envelope wall as that within reduces the potential drop to a negligible amount and thereby minimizes the tendency toward leakage of current from the screen 4 to the outside envelope. The provision of a conducting band about the tube in the foregoing manner insures minimum leakage regardless of changes in atmospheric conditions surrounding the tube and makes it unnecessary to check the calibration of the device with changes in such conditions.

In some installations the cathode ray tube may be in a relatively exposed position so that there may be some chance of the operator's touching the high potential ring. In such installations it is desirable to provide a resistance of several megohms between the ring and the anode terminal 6 as illustrated at 19 in Fig. 4. This resistance limits the current which can be drawn through the ring 16 should the operator come in contact therewith.

The wire ring 16 may be embedded in the collar 7 as illustrated in Fig. 5 where it acts as a reinforcing member for the collar as well as a high potential band for minimizing leakage. Location of the ring 16 in the collar in this manner avoids the necessity of replacing the ring each time a new tube is introduced.

While the invention has been illustrated in connection with a cathode ray tube including a calibrated screen, other applications will readily be apparent to those skilled in the art; for example, it is obvious that other forms of metal bands including coatings on the envelope may be employed instead of a wire ring. It is desired, therefore, not to limit the invention to the specific construction illustrated and described, and it is intended by the appended claims to cover all modifications within the spirit and scope of the invention.

What I claim as new and desire to secure by Letters Patent of the United States, is:

1. In an electron discharge device including an envelope, a luminescent surface positioned on an inner wall of said envelope, a cathode positioned within said envelope, accelerating electrode means located within said envelope between said cathode and said surface, means for impressing on said electrode a potential sufficient to direct electrons emitted by said cathode onto said surface whereby during operation of said device said surface acquires a high positive potential due to secondary emission and tends to produce leakage through said envelope, and means for minimizing leakage through said envelope comprising a conductive band arranged about the outside of said envelope adjacent the periphery of said surface, and means for maintaining said conductive band substantially at the potential of said electrode means comprising a conductive connection between said conductive band and said electrode means.
2. In an electron discharge device including an envelope, means including a cathode and a first anode for developing an electron beam, a luminescent screen on an inner wall of said envelope arranged in the path of said beam whereby said screen acquires a high positive potential due to secondary emission, means including an insulating collar arranged about said envelope adjacent said screen for supporting said device, a band of conducting material arranged about said envelope beneath said collar, and means for connecting said band and said second anode for impressing on said band a positive potential of the same order of magnitude as that on said screen for minimizing leakage through said screen to said supporting means.
3. In an electron discharge device of the cathode ray type having an envelope provided with a luminescent screen on an inner wall thereof and which attains a high positive potential during operation of the device, means surrounding said device adjacent said screen for supporting said device, a wire arranged about said device within said supporting means, and means for impressing on said wire a positive potential of the same order as that existing on said screen during operation of said device whereby leakage through the walls of said device to said support is minimized.
4. In combination, an electron discharge device of the cathode ray type having a luminescent screen on an inner wall surface thereof and which attains a high positive potential during operation of the device due to secondary emission, a conducting member arranged about the outside of said device adjacent said screen, and means including a high resistance element for impressing on said member a high positive potential of the same order of magnitude as that on said screen to minimize leakage from said device and to minimize the flow of current to said conducting member.
5. In combination, an electron discharge device of the cathode ray type having an envelope provided with a luminescent screen on an inner wall thereof, a supporting means for said device comprising a collar of flexible material arranged about said envelope adjacent the periphery of said screen, a conducting member embedded in said collar, and means for impressing on said member a high positive potential of the same order of magnitude as the potential of said screen.

produced by secondary emission whereby leakage through said envelope is minimized.

GEORGE F. DEVINE.
